US00D803218S

(12) **United States Design Patent** (10) **Patent No.:** **US D803,218 S**
Zhou et al. (45) **Date of Patent:** **** Nov. 21, 2017**

(54) **SCANNER**

(71) Applicant: **Hand Held Products, Inc.**, Fort Mill, SC (US)

(72) Inventors: **Peng Zhou**, Suzhou (CN); **Yuefeng Mo**, Suzhou (CN); **Miansong Chen**, Suzhou (CN)

(73) Assignee: **Hand Held Products, Inc.**, Fort Mill, SC (US)

(**) Term: **15 Years**

(21) Appl. No.: **29/598,326**

(22) Filed: **Mar. 24, 2017**

Related U.S. Application Data

(63) Continuation of application No. 29/569,811, filed on Jun. 30, 2016, now Pat. No. Des. 782,481, which is a (Continued)

(74) *Attorney, Agent, or Firm* — Additon, Higgins & Pendleton, P.A.

(57) **CLAIM**

The ornamental design for a scanner, as shown and described.

DESCRIPTION

FIG. 1 is a perspective view of a scanner.

FIG. 2 is another perspective view of the scanner.

FIG. 3 is another perspective view of the scanner.

FIG. 4 is a front elevation view of the scanner.

FIG. 5 is a rear elevation view of the scanner.

FIG. 6 is a left side elevation view of the scanner.

FIG. 7 is a right side elevation view of the scanner.

FIG. 8 is a top plan view of the scanner; and,

FIG. 9 is a bottom view of the scanner.

Broken lines shown in the drawings of the scanner are for illustrative purposes only and form no part of the claimed design.

1 Claim, 7 Drawing Sheets

Related U.S. Application Data

continuation of application No. 29/524,186, filed on Apr. 17, 2015, now Pat. No. Des. 760,719.
